Primary Examiner — Carol P Rademaker(74) *Attorney, Agent, or Firm* — Leydig, Voit & Mayer, Ltd.; John Augustyn(57) **CLAIM**

The ornamental design for a bottle and cap, as shown and described.

DESCRIPTION

FIG. 1 is a top, front, left side perspective view of a bottle with cap of the new design;

FIG. 2 is a top plan view thereof;

FIG. 3 is a bottom plan view thereof;

FIG. 4 is a front elevational view thereof;

FIG. 5 is a back elevational view thereof;

FIG. 6 is a right side front elevational view thereof; and,

FIG. 7 is a left side elevational view thereof.

The broken lines of the central portion of the bottom surface shown in the drawings are included for the purpose of illustrating environmental structure and form no part of the claimed design.
